UNITED STATES PATENT OFFICE.

AXEL B. SKEPPSTEDT AND ELI HADDON, OF CHICAGO, ILLINOIS, SAID HADDON
ASSIGNOR TO FRANK LITRELL, OF CHICAGO, ILLINOIS.

PASTING MACHINE.

Application filed January 9, 1922. Serial No. 527,958.

To all whom it may concern:

Be it known that we, AXEL B. SKEPPSTEDT and ELI HADDON, citizens of the United States, residing at Chicago, in the county of 5 Cook and State of Illinois, have invented new and useful Improvements in Pasting Machines, of which the following is a specification.

The machine which is the subject matter 10 of the present application for patent has been designed for attaching additional or insert sheets to the signatures or other sections of books, and it is the object of the invention to provide a machine of novel and improved 15 construction and operation whereby the attachment of the sheets to the signatures is automatically effected, all manual operations excepting that of feeding the signatures and the sheets to the machine being 20 eliminated.

A further object of the invention is to provide a machine of the kind stated which is rapid and accurate in operation.

Other objects and advantages of the invention will appear in the detailed description hereinafter.

In order that the invention may be better understood, reference is had to the accompanying drawings, forming a part of this 30 specification, and in said drawings:

Figure 1 is a plan view of the machine; Fig. 2 is a side elevation thereof; Fig. 3 is an elevation viewed from the other side; Fig. 4 is a cross-section on the line 4—4 of 35 Fig. 1; Fig. 5 is a longitudinal section on the line 5—5 of Fig. 1; Fig. 6 is a sectional detail, largely diagrammatic, illustrating the paste applying operation, Fig. 7 is an enlarged sectional view on the line 7—7 of 40 Fig. 1, and Fig. 8 is a similar view on the line 8—8 of Fig. 3.

Referring specifically to the drawings, the supporting frame of the machine comprises a pair of parallel and laterally spaced longitudinal side rails 10 supported by legs 11 which are connected by a suitable arrangement of tie bars and braces, the side rails 10, near one end of the machine carrying depending bearing brackets 12 supporting a 50 main drive shaft 13 which obtains power from an electric motor 14 supported on a shelf 15 carried by the frame beneath the side rails. A belt drive 16 is shown, but any other driving connection between the motor 55 14 and the shaft 13 may be provided, and the

shaft may also obtain power from any other source. At the other end of the machine, the legs 11 carry bearings 17 which support a countershaft 18 obtaining motion from the main drive shaft 13, a chain or other suitable driving connection 19 being provided.

Each side rail 10 carries an upstanding edge guide 20 for the work, the same extending in the direction of the length of the machine. Between the guides 20 are positioned several rollers 21 having their axes parallel to said guides. Two sets of these rollers are provided, there being three rollers in each set. One set of rollers is adapted to be rotated in a direction to urge the work laterally toward one guide 20, and the other set of rollers rotate in an opposite direction to urge the work laterally toward the other guide 20. The driving means for the rollers 21 comprise bevel gears 22 on one end thereof and meshing with bevel gears 23 on a transverse shaft 24 provided with a pinion 25 which is in mesh with a spur gear 26 on a transverse shaft 27. On shaft 27 are two sprocket wheels 28 which are connected by 75 chains 29 to sprocket wheels 30 on a transverse shaft 31 at the other end of the machine. Shaft 31 obtains motion from shaft 13 through a short shaft 32 having bevel gears 33 and 34 at its ends, one of which is 80 in mesh with a bevel gear 35 on shaft 13 and the other with a bevel gear 35^a on shaft 31.

The chains 29 run parallel to the rollers 21, there being one chain for each set of rollers. Between the chains and the rollers 90 are filler strips 36 extending throughout the entire length of the machine. These strips form a work-supporting surface or table along which the work is fed by the chains 29, the latter being armed with fingers 95 37 which project above the table top to engage the work. The fingers may be in the form of rollers mounted on studs carried by the chain. The rollers 21 also project slightly above the top of the table so that they may 100 come into contact with the under side of the work and carry the same laterally in the direction of the edge guides 20.

Intermediate the ends of the machine, the guides 20 carry a pair of cross bars 38 which are spaced in the direction of the length of the machine and support two pairs of shelves, the members of which are indicated at 39 and 40. The members of the respective pairs of shelves are spaced at their inner 110

longitudinal edges so that the fingers 37 of the chains 29 may extend into the spaces. One shelf 39 has its inner edge alongside one guide 20, and the other shelf 39 has its inner edge alongside the other guide 20. The outer edges of the shelves 40 have upstanding work guiding flanges 41. The shelves are designed to receive the sheets to be attached to the signatures, and they are spaced a sufficient distance from the strips 36 forming the table top along which the signatures are fed to allow the latter to pass.

The shelves 40 are adjustably carried by the cross bars 38 so that they may be adjusted laterally with respect to the shelves 39 according to the width of the work. The attachment is made by clamps 42 on the shelves 40 and carrying set screws 43 for engaging the cross bars.

20 In the operation of the machine, paste is applied to the signature just before it passes under a pair of shelves 39 and 40, and the sheet to be attached is placed on said shelves. The finger 37 of the chain 29 which feeds the signature along beneath the shelves also feeds the sheet as it engages the rear edge thereof, and the sheet is now carried along with the signature but spaced therefrom vertically by the shelves. When the signature 25 issues from beneath the shelves and the sheet leaves the exit end of the latter, it drops down on the signature and is carried along with the latter to a presser device comprising two pairs of rollers 44 and 45 between 30 which the signature and the superimposed sheet is fed. The rollers 44 press the sheet into intimate contact with the pasted portion of the signature, which completes the operation, the finished work being discharged on 35 a suitable holder 46 as it issues from the presser rollers.

The rollers 44 are on the shaft 31, and the rollers 45 are on a shaft 47 obtaining motion from shaft 31 through a pinion 48 on one shaft meshing with a pinion 49 on the 40 other shaft.

The shaft 47 is supported by bracket arms 50 fastened to and extending laterally from a rock-shaft 51 supported in bearings 52 on the side rails 10 and provided with handles 53. By operating the shaft 51, the shaft 47 45 may be swung to carry the rollers 45 away from and out of operative relation with respect to the rollers 44. The bracket arms 50 are adjustably fastened to the rock shaft 51 by set screws 54.

At 55 is shown a paste reservoir. It will be understood that the machine will be provided with two paste reservoirs, one for each unit. However as the construction and operation of the two reservoirs is the same, a description of one suffices for both. The reservoir has a bottom outlet in which works a protruding distributing roller 56 carried 60 by a transverse shaft 57 on one end of which

is a pinion 58 which is in mesh with a pinion 59 loose on a shaft 60 parallel to the roller shaft 57. Pinion 59 is fastened to one side of a sprocket wheel 61 also loose on shaft 60 and connected by a drive chain 62 to a sprocket wheel 63 on the shaft 27.

The reservoir 55 is supported by the shaft 60, the attachment being made by a suitable bracket member 64. The shaft 60 is adapted to be rocked for the purpose of tilting the reservoir 55 forwardly to lower the roller into contact with the signature along the edge to which the sheet is to be attached, this edge being along the guide 20. In order that this tilting movement of the reservoir may not disengage the pinions 58 and 59, the shaft 57 is supported by rocker arms 65 carried by the shaft 60, and hence said shaft swings with the reservoir when the latter is tilted. The following means are provided for tilting the reservoir:

The side rails 10 carry bearings 66 in which the shaft 60 is journaled, and to one end of the shaft is connected a rocker arm 67 to which latter in turn is connected, intermediate its ends, a pitman 68 obtaining motion from the counter-shaft 18. The inner end of the pitman 68 is fitted with a fork 69 which slidably straddles the shaft 18, and on one side of the fork is mounted a roller 70. On the shaft 18 is fixed a cam or wiper 71 which, when the shaft is in motion, strikes the roller 70 at every revolution of the shaft, whereby, through the pitman 68, the arm 67 is swung to rock the shaft 60 in one direction. To the outer end of the arm 67 is connected one end of a rod 72 having its other end slidably supported by a suitable support 73 on one of the frame legs 11. Between the support 73 and an abutment 73^a on the slide rod 72 is a spring 74, the same being coiled around the rod. When the cam 71, through the pitman 68, swings the arm 67 as hereinbefore described, the spring 74 is compressed as the rod 72 slides, and when the cam clears the roller 70, the spring expands and through the rod 72 swings the arm 67 in an opposite direction, so that the shaft 60 is now again rocked, but in a direction opposite from that in which it was rocked by the operation of the cam as hereinbefore described. By this operation the shaft 60, is rocked and the reservoir 55 carried thereby is tilted.

On the shaft 18, alongside the cam 71 is loosely mounted a second cam 75 adapted to be adjusted to form a continuation of the cam 71 for the purpose of timing the tilting of the reservoir 55. The cam 75 has an arcuate slot 76 through which passes a stud 77 extending from one side of the cam and carrying a nut 78 for locking the cam to the main cam 71. By shifting the cam 75 so that it projects beyond one edge thereof as shown in Fig. 3, the tilting movement of

the reservoir will occur earlier, and in this way an accurate adjustment may be made so that the reservoir remains tilted downwardly long enough to apply paste to one 5 signature.

The operation of the machine may be summarized as follows:

- A stack of signatures is supported on a shelf 79 extending from one side of the 10 machine, and alongside said shelf is a second shelf 80 supporting a stack of the sheets which are to be pasted to the signatures. If both units are to be operated, signature and sheet supporting shelves will be attached to 15 the other side of the machine also. One operator is provided for each shelf for feeding the contents thereof to the machine. The machine being in motion, a signature is placed on the forward end of the table or 20 work supporting surface formed by the filler pieces 36 and a sheet is placed on one of the pairs of shelves 39 and 40. The signature is placed so that it will be worked over by the rollers 21 against the guide 20 on the 25 same side of the machine as the shelves on which the sheet was placed. Now when the rear edge of the signature is engaged by one of the projecting fingers 37 of the chain 29, the signature is pushed in the direction 30 of the shelves and the paste reservoir associated therewith. The signature is then pushed past the distributing roller 56 and a narrow strip of paste is applied, the paste reservoir having in the meantime been tilted 35 to bring the roller in operative relation with respect to the signature, and when the latter clears the roller the reservoir is tilted back to elevate the roller. The signature next passes beneath the shelves 39 and 40 on 40 which the sheet is lying, and when the chain finger which is propelling the signature reaches the rear edge of the sheet the sheet starts to travel along with the signature. When the sheet reaches the rear end of the 45 shelves it drops down on the signature, and the latter and the sheet travel together in superimposed relation to the presser rollers 44 and 45. During the travel of the signature to the paste-applying apparatus it is 50 continuously urged by the rollers 21 in a lateral direction to keep one of its longitudinal edges in contact with the guide 20, and the same action takes place when the signature and the superimposed sheet are 55 traveling toward the presser rollers 44 and 45. By this operation the two parts are so guided that the sheet is accurately pasted to the signature. It will be noted that the sheet-exit end of the shelf 39 terminates 60 short of the corresponding end of the shelf 40, with the result that the portion of the sheet which is to be pasted to the signature first drops down to catch the coated portion of the signature. While traveling along the

shelves 39 and 40, the sheet is guided by the 65 guide 20 and the flange 41.

The connection between the arm 67 and the rock shaft 60 is an adjustable one. As shown in Figures 7 and 8 the shaft 60 passes loosely through a hub 67^a on the arm 67, 70 and on the end of the shaft is fastened a crank member 80 having at its outer end a laterally extending portion 81 which overhangs the shaft and has a slot or recess 82 extending transversely of the shaft. The 75 upper end of the arm 67 extends into the recess 82 and is here engaged on opposite sides by adjusting screws 83 threaded through the sides of the part 81. By means of these screws, the shaft 60 carrying the 80 reservoir 55 may be rocked to tilt the reservoir, and in this manner the paste-applying roller 56 is adjusted according to the thickness of the signatures, the reservoir being tilted back when the machine is to operate 85 on signatures containing a large number of sheets, and tilted forwardly when the signatures contain fewer sheets. The paste-applying mechanism can therefore be accurately adjusted to signatures varying in 90 thickness.

The operation of the cam mechanism which actuates the arm 67 is so timed that the reservoir 55 tilts to bring the roller 56 to paste-applying position shortly after the 95 forward edge of the signature has passed the roller, and the reservoir is tilted back to remove the roller from the signature before the rear end of the signature reaches the roller. In this manner paste is not applied to the signatures adjacent to the ends thereof, which is desirable for the reason that if the paste extended throughout the entire length of the signature it would be squeezed out at the ends when the insert sheet is pressed on by the rollers 44 and 45. The adjustment of the cam mechanism hereinbefore described enables the length of the working strokes of the roller 56 to be varied according to the length of the signatures. In order to hold down the signature as it passes to the paste-applier, especially if its forward edge has a tendency to curl upwardly, there is mounted close to the roller 56 a flexible guard plate 84, beneath which the signature passes, said plate being carried by a cross bar 85 supported by the guides 20. 100 105 110 115

We claim:

1. In a pasting machine, a work-supporting surface, a pair of laterally spaced work-supporting shelves positioned intermediate the ends of said surface in vertically spaced relation therewith, a work-edge guide extending in the direction of the length of the work-supporting surface and along one of the shelves, a work-edge-guide on the other shelf, said shelf being adjustable laterally with respect to the first-mentioned shelf, 120 125

- means for feeding work along the work-supporting surface and off the shelves, and means for coating the work fed along said surface.
5. 2. In a pasting machine, a work-supporting surface, a pair of laterally spaced work-supporting shelves positioned intermediate the ends of said surface in vertically spaced relation therewith, means for feeding work 10 along the work-supporting surface and off the shelves onto the work on said surface, and a paste-applying means operating on the work fed along said surface, said means being located adjacent to one end of the shelves, and one of said shelves terminating at its other end short of the corresponding end of the other shelf.
15. 3. In a pasting machine, a work-supporting surface, a pair of laterally spaced work-supporting shelves positioned intermediate the ends of said surface in vertically spaced relation therewith, means for feeding work 20 along the work-supporting surface and off the shelves, the work fed off the shelves being delivered onto the work fed along the supporting surface beyond the work exit ends of the shelves, paste-applying means operating on the work fed along the supporting surface, said means being located adjacent to one end of the shelves, and presser devices located beyond the other ends of the shelves.
25. 4. In a pasting machine, a work-supporting surface, a pair of laterally spaced work-supporting shelves positioned intermediate the ends of said surface in vertically spaced relation therewith, means for feeding work 30 along the work-supporting surface and off the shelves onto the work on said surface, a paste-applying means operating on the work fed along said surface, said means being located adjacent to one end of the shelves, and one of said shelves terminating at its other end short of the corresponding end of the other shelf, and a presser device located beyond the last-mentioned ends of the shelves.
35. 5. In a pasting machine, a work-supporting surface, a pair of laterally spaced work-supporting shelves positioned intermediate the ends of said surface in vertically spaced relation therewith, means for feeding work 40 along the work-supporting surface, and off the shelves onto the work on said surface, a paste-applying means operating on the work fed along said surface, said means being located adjacent to one end of the shelves, and one of said shelves terminating at its other end short of the corresponding end of the other shelf, and a presser device located beyond the last-mentioned ends of the shelves.
45. 6. In a pasting machine, a work-supporting surface, a pair of laterally spaced work-supporting shelves positioned intermediate the ends of said surface in vertically spaced relation therewith, means for feeding work 50 along the work-supporting surface, and off the shelves onto the work on said surface beyond one end of the shelves, a paste-applying means operating on the work fed along the supporting surface, said means being located adjacent to the other ends of the shelves, a work edge-guide extending along the work-supporting surface, and means for carrying the work on said surface in a lateral direction into engagement with the edge-guide.
55. 7. In a pasting machine, a work-supporting surface, a pair of laterally spaced work-supporting shelves positioned intermediate the ends of said surface in vertically spaced relation therewith, means for feeding work 60 along the work-supporting surface, and off the shelves onto the work on said surface beyond one end of the shelves, a paste-applying means operating on the work fed along the supporting surface, said means being located adjacent to the other ends of the shelves, a work edge-guide extending along the work-supporting surface, and means for carrying the work on said surface in a lateral direction into engagement with the edge-guide.
65. 8. In a pasting machine, a work-supporting surface, a pair of laterally spaced work-supporting shelves positioned intermediate the ends of said surface in vertically spaced relation therewith, means for feeding work 70 along the work-supporting surface, and off the shelves onto the work on said surface beyond one end of the shelves, a paste-applying means operating on the work fed along the supporting surface, said means being located adjacent to the other ends of the shelves, a work edge-guide extending along the work-supporting surface, and means for carrying the work on said surface in a lateral direction into engagement with the edge-guide, said means operating beyond both ends of the shelves.
75. 9. In a pasting machine, a work-supporting surface, a pair of laterally spaced work-supporting shelves positioned intermediate the ends of said surface in vertically spaced relation therewith, means for feeding work 80 along the work-supporting surface and off the shelves, the work fed off the shelves being delivered onto the work fed along the supporting surface beyond the work exit ends of the shelves, paste-applying means operating on the work fed along the supporting surface, said means being tiltable and located adjacent to one end of the shelves, and presser devices located beyond the other ends of the shelves.
85. 10. In a pasting machine, a work-supporting surface, a pair of laterally spaced work-supporting shelves positioned intermediate the ends of said surface in vertically spaced relation therewith, means for feeding work 90 along the work-supporting surface and off the shelves, the work fed off the shelves being delivered onto the work fed along the supporting surface, said means being tiltable and located adjacent to one end of the shelves, and presser devices located beyond the other ends of the shelves.
95. 11. In a pasting machine, a work-supporting surface, a work edge-guide extending lengthwise of said surface, means for feeding work 100 along the surface, and rollers protruding from said surface for engaging the work, said rollers being rotatable in a direction to carry the work laterally into engagement with the edge-guide.
100. 12. In a pasting machine, a work-supporting surface, a work edge-guide extending lengthwise of said surface, means for feeding work 105 along the surface, rollers protruding from said surface for engagement by the work, said rollers having their axes parallel to the direction the work is fed, and means for rotating the rollers in a direction to carry the work laterally into engagement with the edge-guide.
105. 13. In a pasting machine, a work-supporting surface, a work edge-guide extending lengthwise of said surface, an endless chain running in the direction of the length of the surface and having work-engaging projections for feeding work along the surface, rollers protruding from said surface for engagement by the work, said rollers having their axes parallel to the direction the chain travels, and means for rotating the rollers in a direction to carry the work laterally into engagement with the edge-guide.
110. 14. In a pasting machine, a work-supporting surface, a work edge-guide extending lengthwise of said surface, an endless chain running in the direction of the length of the surface and having work-engaging projections for feeding work along the surface, rollers protruding from said surface for engagement by the work, said rollers having their axes parallel to the direction the chain travels, and means for rotating the rollers in a direction to carry the work laterally into engagement with the edge-guide.
115. 15. In a pasting machine, a work-supporting surface, a paste-applier above said surface, a support for said applier to permit a movement thereof toward and from the work, means for feeding work along the supporting surface, means for moving the paste- 120
125. 16. In a pasting machine, a work-supporting surface, a paste-applier above said surface, a support for said applier to permit a movement thereof toward and from the work, means for feeding work along the supporting surface, means for moving the paste- 130

applier to work engaging position after the work passes the same, and for moving the paste-applier away from the work before the same clears said applier, and an actuator for the applier moving means adjustable to time the interval between the working strokes of the applier.

12. In a pasting machine, a work-supporting surface, a paste-applier above said surface, a support for said applier to permit a movement thereof toward and from the work, means for feeding work along the supporting surface, means for moving the paste-applier to work engaging position after the work passes the same, and for moving the paste-applier away from the work before the same clears said applier, said paste-applier being also adjustable to obtain a variable working stroke, and an actuator for the applier moving means adjustable to time the interval between the working strokes of the applier.

13. In a pasting machine, a work-supporting surface, means for feeding work along said surface, a paste-applier, a rock-shaft carrying said applier and operable to bring the same into and out of contact with the work, a rocker-arm loose on said shaft, a crank-member fast on said shaft and having a recess into which one end of the rocker-arm extends, screws threaded through opposite walls of said recess to engage opposite sides of the rocker-arm, and actuating means for the rocker-arm.

14. In a pasting machine, a work-supporting surface, means for feeding work along said surface, a paste-applier, a rock-shaft carrying said applier and operable to bring the same into and out of contact with the work, a rocker-arm loose on said shaft, a crank-member fast on said shaft and having a laterally extending portion which overhangs the rock-shaft and has a recess, screws threaded through opposite walls of said recess to engage opposite sides of the rocker-arm, and actuating means for the rocker-arm.

15. In a pasting machine, a work-supporting surface, means for feeding work along said surface, a paste-applier, a tilttable support for the paste-applier, and operating means for the tilttable support, said means including a cam, a drive shaft carrying said cam, and a second cam on said shaft and adjustable to form a continuation of the first- 55 mentioned cam.

16. In a pasting machine, a work-supporting surface, means for feeding work along said surface, a paste-applier, a tilttable support for the paste-applier, a rocker-arm operatively connected at one end to the support, a slidably supported rod connected to the other end of the rocker-arm, an abutment on said rod, a spring engageable with the abutment for moving the rod in one direction and thereby swing the rocker-arm in one direction, and means for swinging the rocker-arm in the opposite direction, said means comprising a pitman connected to the rocker-arm, and a cam engageable with said 70 pitman.

17. In a pasting machine, a work-supporting surface, means for feeding work along said surface, a paste-applier, a tilttable support for the paste-applier, a rocker arm operatively connected at one end to the support, a slidably supported rod connected to the other end of the rocker-arm, an abutment on said rod, a spring engageable with the abutment for moving the rod in one direction and thereby swing the rocker arm in one direction, and means for swinging the rocker-arm in the opposite direction, said means comprising a pitman connected at one end to the rocker arm, a drive shaft slidably 80 engageable by the other end of the rocker arm, said end being forked to straddle the shaft and carrying a roller, and a cam on the shaft engageable with said roller.

In testimony whereof we affix our signatures.

AXEL B. SKEPPSTEDT.
ELI HADDON.
